AUTOMOBILE TRUNK

Charles J. Carlson, Helena, Mont.

Application April 10, 1930, Serial No. 443,209

5 Claims. (Cl. 224—29)

This invention relates to automobile trunks and a primary object thereof is to so construct a trunk of this character that it will be convertible to form either a closed container or opened up to provide an enlarged uncovered luggage carrier.

Another object is to construct a trunk of this character, the sections of which are so connected that when opened up to form additional space will be firmly and rigidly held while extended and which may be quickly set up when desired to obtain a closed container having all the attributes of a trunk.

In carrying out these objects, the invention is susceptible of a wide range of modification without departing from the spirit or sacrificing any of the advantages of the claimed invention; there being shown in the drawings for illustrative purposes a preferred and practical form, in 20 which:

Fig. 1 represents a perspective view of the rear portion of an automobile with this improved trunk shown applied;

Fig. 2 is an end elevation of the trunk shown 25 in opened up position to form an enlarged luggage carrier;

Fig. 3 is an enlarged vertical section taken on the line 3—3 of Fig. 1;

Fig. 4 is a horizontal section taken on the line 30 4—4 of Fig. 1;

Fig. 5 is a longitudinal vertical section taken on the line 5—5 of Fig. 1;

Fig. 6 is a detail sectional view taken on the line 6—6 of Figure 3, the top having been raised 35 to permit swinging the catch handle to the locking position.

Fig. 7 is a transverse section taken on the line 7—7 of Fig. 2;

Fig. 8 is a detail sectional view showing one 40 of the fasteners used for holding the trunk in closed upstanding position.

Fig. 9 is a detail section taken on the line 9—9 of Fig. 2, illustrating how the opening of the movable section is limited by the engagement of 45 certain stops and shoulders.

Fig. 10 is a detail perspective view of a portion of the movable section, particularly showing one of the shoulders.

Fig. 11 is a detail perspective view of a portion of the fixed section, particularly showing the stops and guides.

In the embodiment illustrated the trunk constituting this invention comprises two hingedly connected sections which will be termed fixed and movable sections. The fixed section includes

a bottom 1 provided at its opposite ends with brackets 2 for mounting it on an automobile frame indicated at F. The movable section comprises a bottom member 3 which is connected at its lower edge with the front edge of the bottom 1 by a double hinge 4 to provide for the flexible operation of the guides which connect the sections of the trunk as will be hereinafter more fully described. This member 3 which constitutes the bottom of the movable section when open, when closed forms the front wall of the trunk.

Rising from the ends of the bottom 1 are two end or side members 5 and 6 which are inclined forwardly and downwardly at their upper edges as shown at 7 in Fig. 2. A shelf or bar 8 connects the upper rear portion of the end members as shown clearly in Fig. 3. Curved guides 9 are carried by the outer face of each of the end members 5 and 6. The guides 9 are spaced a slight distance 25 (Fig. 7) from the adjacent face of the respective section. Base portions 26 serve as connectors between the guides 9 and the end members 5, 6. The spaces make room for the tongues 27 (Fig. 10) of interlocking bracing elements 10. These elements ride in the spaces, the tongues 27 being behind the guides 9 and thereby keeping the side members 11 and 12 of the section 3 from spreading, especially when open. Connecting parts 28 (Figs. 2, 9 and 11) provide stops for limiting the outward swing of the movable section. This is accomplished by the engagement of these stops by the shoulders 29 of the elements 10 (Fig. 9). A marginal piece 30, applied to each side member 11, 12 (Figs. 7 and 10) has hook ends 31 which engage the uppermost guides 9 and assist the function of the elements 10. The side members 11 and 12 carried by the movable section overlap the members 5 and 6 of the fixed section when the sections are closed. It will thus be seen that the movable section is composed of the member 3 which forms a bottom when in open position and a front when in closed position. Said section also includes a hinged top 13 which latter constitutes the hinged top of the trunk when the sections are closed. When folded down in the position shown in Fig. 2 a large open luggage carrier is formed the rear end of which is formed by the hinged cover 13 which is held closed by suitable fastenings 14.

A cross bar 15 connects the upper edges of the end members 11 and 12 and to this cross bar is hingedly connected at its rear edge the top 13 as is shown clearly in Fig. 3. A catch member 16

16 is carried by the cross bar 15 and is designed to engage a cooperating element carried by the lip or cross bar 8 which connects the upper ends of the end members 5 and 6 and which is here shown in the form of a slot 16^a to receive the catch member 16 which latter is equipped with an operating handle 17 and by means of which the movable section and the fixed section of the trunk are secured in closed operative position. 5 When the top 13 is locked in the closed position the seclusion of the handle 17 will prevent the undoing of the catch 16 and so the opening of the movable section. The top 13 holds the handle 17 down as long as it remains closed. 10 Certain free edges of the members 11 and 12 are preferably provided with a reinforcing band or strip 18 and from the upper ends of this strip near the top are laterally projecting studs 19 designed to be interlockingly engaged with co- 15 operating eyes 20 carried by the fixed portion of the trunk when the movable section is in closed position as is shown in Fig. 1.

The back 21 of the trunk proper is made in the form of a removable plate slidably mounted in guides 22 carried by the rear edges of the members 5 and 6 as shown clearly in Fig. 4. This plate 21 may, if desired, be bolted to these guides to avoid all danger of its working loose or rattling. A similar guide or keeper 23 is formed 25 along the rear edge of the bottom 1 as shown in Fig. 3 to receive the lower edge of the plate 21 when in operative position.

Handles 24 are preferably provided at the opposite ends of the trunk to facilitate the manipulation thereof.

From the above description it will be obvious that when the trunk is designed to be used as such to provide a closed container, the parts are positioned as shown in Figs. 1 and 3 and to obtain access thereto all that is necessary will be 35 to raise the top 13. When it is desired to provide more space the top 13 is raised in order to get at the handle 17 for the release of the catch 16, whereupon the top is securely fastened to the front member 3 and the fastening elements 19 and 40 20 at the ends of the trunk are disengaged. Then a forward pull exerted on the front portion of the trunk will cause it to move downwardly, guided in its movement by the sliding of interlocking elements 9 and 10 carried by the fixed 45 and movable end members respectively until it reaches the position shown in Figs. 2 and 9, in which position it will be held by the engagement 50 of the stops 28 at the ends of the cooperating guides, by the shoulders 29 as previously explained. The double hinge 4 enables the easy 55 turning of the movable trunk section in this respect that should there be any slight misalignment of the interlocked guides 9 and bracing elements 10 such misalignment will be compensated 60 for by a yielding of the hinge.

This convertible trunk and luggage carrier may be readily changed from an open to a closed

container or vice versa and will be securely held in either of its positions.

When the trunk is in the open position shown in Fig. 2 the carrying space will be substantially double that when it is in upright closed position and when in either position it will present a neat attractive appearance.

In carrying out these objects, the invention is susceptible of a wide range of modification without departing from the spirit or sacrificing any of the advantages of the claimed invention; there being shown in the drawings for illustrative purposes a preferred and practical form, in which:

I claim:

1. A trunk comprising a fixed section including a cross bar, a movable section also including a cross bar, latch means carried by one of the bars and being movable into a latching position with reference to the other bar to lock the two sections in the closed position, and a top hingedly carried by the cross bar of the movable section in a position to cover the latch means and required to be raised for access to the latch means.

2. A trunk comprising a fixed section including a cross bar, a movable section also including a cross bar, said cross bars coming into confronting relationship when the sections are moved into a closed position with respect to each other, latch means carried by one of the bars including a handle for moving the latch means into locking relationship with the other bar, and a top hingedly carried by the movable section, said top being closable to prevent reverse movement of the handle and prevent access to the latch means while said top is closed.

3. A trunk comprising a fixed section, a movable section, latch means carried by one of the sections including a handle for moving the latch means into locking relationship with the other section, a top hingedly carried by one of the sections, said top being closeable to prevent reverse movement of the handle and prevent access to the latch means while said top is closed.

4. A trunk comprising a pair of sections having overlapping ends, arcuate guide means on at least one end of one section and interengaging stop means on the adjacent end of the other section, said stop means being slideable along the arcuate guide means, and double-action hinge means connecting the sections for opening and closing, the double action of said hinge means enabling compensation for any misalignment of the stop and guide means.

5. A trunk comprising a pair of sections having overlapping ends, arcuate guide means on at least one end of one section and interengaging stop means on the adjacent end of the other section, said stop means being slideable along the arcuate guide means, and means including a double hinge connecting the sections for opening and closing, said means being yieldable to compensate for any misalignment of the stop and guide means.

CHAS. J. CARLSON.
